UNITED STATES PATENT OFFICE

159,487

FURNACE FRONT

Richard C. Jaye, Milwaukee, Wis., assignor to Syncromatic Corporation, Watertown, Wis., a corporation of Wisconsin

Application October 7, 1948, Serial No. 148,999

Term of patent 14 years

(Cl. D81—1)

To all whom it may concern:

Be it known that I, Richard C. Jaye, a citizen of the United States of America, residing at Milwaukee, in the county of Milwaukee and State of Wisconsin, have invented a new, original, and ornamental Design for Furnace Front, of which the following is a specification, reference being had to the accompanying drawing, forming part thereof.

I claim:

The ornamental design for a furnace front, as shown.

RICHARD C. JAYE.
